UNITED STATES PATENT OFFICE.

SHELDON J. GLASS, OF MILWAUKEE, WISCONSIN.

COIN-BOX FOR COIN-CONTROLLED MECHANISM.

SPECIFICATION forming part of Letters Patent No. 601,251, dated March 29, 1898.

Application filed June 25, 1897. Serial No. 642,219. (No model.)

To all whom it may concern:

Be it known that I, SHELDON J. GLASS, a citizen of the United States, and a resident of Milwaukee, in the county of Milwaukee and State of Wisconsin, have invented certain new and useful Improvements in Coin-Boxes for Coin-Controlled Mechanism; and I do hereby declare that the following is a full, clear, and exact description thereof.

10 My invention relates to coin-boxes for coin-controlled mechanism; and it consists in certain peculiarities of construction and combination of parts, as will be fully set forth hereinafter and subsequently claimed.

15 In the drawings, Figure 1 is a central vertical longitudinal sectional view of my device on the line 1 1 of Fig. 2. Fig. 2 is a central vertical transverse sectional view of the same on the line 2 2 of Fig. 1. Figs. 3 and 4 are 20 sectional views on the same line as in Fig. 2, but with the movable parts in different positions. Figs. 5 and 6 are end views of the device.

25 Referring to the drawings, A represents a block of any suitable metal with a straight-walled vertical opening therethrough of a size just sufficient for the passage of a coin of predetermined size, said opening being herein termed the "coin-slot" B. Further, the said 30 block is formed with two longitudinally-disposed cylindrical bores extending from one end almost to the opposite or outer end and arranged one above the other to receive the hereinafter-described cylinders, and the said 35 outer end being formed with bores of lesser diameter to receive the outer trunnions or journals of said cylinders. These cylindrical bores intersect the described coin-slot B, and the walls of said coin-slot are preferably en- 40 larged, or flared, or beveled outwardly at said points of intersection.

45 D is the upper cylinder, preferably solid, save for a longitudinal slot a cut therein and extending nearly but not quite through said cylinder, this slot a corresponding in dimensions to the described coin-slot B in the block A and exactly registering therewith when the said cylinder D is in the position shown in Figs. 1 and 2, with the opening of 50 the slot a uppermost to receive a coin E or when said cylinder has made a half-revolu-

tion to discharge the coin therefrom, as shown in Fig. 3.

C is a plate secured to the inner end of the block A, as by screws b b, and formed with 55 bores therethrough for the trunnions of the cylinders, the upper bore in said plate receiving the trunnion c of the cylinder D, while the trunnion d of said cylinder projects through the upper bore in the outer end of 60 the block A and there receives a disk F, whose periphery or segment thereof is formed with teeth to mesh with the like teeth on a lower disk G, hereinafter described. The disk F is formed or provided with stops e f for engage- 65 ment with like stops g h on the lower disk G, as hereinafter described. In the construction illustrated in the drawings these stops consist of the straight parallel upper and lower ends of metallic pieces rigidly secured 70 to the disks F G, it being only essential that each of these disks F G should carry therewith projections adapted to come into contact at the half-revolution of said disks in either direction and thereby prevent the further 75 movement of said disks in that direction. In Fig. 6 the stop or projection e on disk F is in contact with the stop or projection g on disk G, and when the said disks F G are turned in the opposite direction (by the hand-wheel j) the stop or projection f on disk F will come in contact with the stop or projection h on disk G and thereby stop the movement of said disks in that direction at a half-revolution thereof. 85

The lower cylindrical bore in the block A is for the reception of the double concentric coin-shells H I, nested together, as best shown in Fig. 1. The head of the coin-shell H is provided with a shaft i, extending through 90 the lower bore in the outer end of the block A, and having secured to it the described disk G, beyond which said shaft carries a hand-wheel j, while the inner face of the head of said shell H is formed with a conical concave 95 seat k. m is the outer and n the inner shell of the said coin-shell H, the shell m resting on an annular shoulder on the inner side of the head of the coin-shell I, which latter part has also an outer shell o, projecting between 100 the shells m and n of the other part, and a shell p within the said shell n, when the two

parts II and I are nested together, as shown and described. Further, the part I has an inwardly-projecting shaft *q*, terminating in a pointed conical end *r*, fitting within the described conical seat *k* in the head of the part H, while from the outer side of the head of the part I there projects a journal or shaft *s*, extending through the lower bore in the plate C, beyond which said shaft carries a ratchet-wheel J.

K is a spring-pawl secured to the plate C and in engagement with the ratchet-wheel J, and L is a pin on said plate C, against which the said pawl K bears.

M is a top plate of hardened steel, secured to the block A in any suitable manner, as by screws *t* *t*, and formed with a slot *u* therethrough, which slot exactly registers with the described coin-slot B. It will be understood that the said block A is designed to be secured in a suitable casing, so that the screws herein shown will not be exposed but will be wholly covered up, as will be the described disks or segments F G and ratchet-wheel J and pawl K, all as indicated by the double dotted lines in Fig. 1, and that a proper receptacle is provided in said casing below the bottom of the block A for the coins from the slot B to drop into, and that said receptacle is to be provided with a proper locked door; but as such casing, coin-receptacle, and locked door are common to all devices of this kind and form no part of my present invention I have not deemed it necessary to illustrate the same.

All of the concentric shells of the parts II I are formed with slots therethrough, there being only one slot in the outer shell *m* of the part II and two registering slots through the inner shell *n*. The shells *o* *p* and central shaft *q* of the part I are all provided with slots registering with each other, and these slots in the part I are brought in line with the described slots in the part H only when the stops on the disks F G are in engagement.

The operation of my device will be readily understood from the foregoing description of its construction, taken in connection with the accompanying drawings. As is well known, the class of apparatus to which devices such as I have described are particularly applicable embrace such as are designed to contain or control a supply of vendible articles or material as well as such as have movable parts adapted to be set in motion or to have their movements controlled or regulated, or said movable parts released or permitted to be set in motion by means of a coin of predetermined dimensions dropped into the coin-box, and hence it is desirable that such coin-box should be so constructed as to prevent any tampering with the same or the withdrawal of any coin deposited therein or any access to the operating devices save by the proper deposit of the required coin, and these objects are attained by my construction, the operation being as follows: The hand-wheel

j is turned to bring the parts into the relative positions shown in Figs. 1, 2, and 6, this being accomplished by the movement of the intermeshing toothed disks or segments F G until such movement is stopped at the end of a half-revolution by the engagement of the stops *e* *g*. A coin E of the proper size is then dropped through the slot *u* in the top plate M and the upper part of the coin-slot B into the slot *a* in the cylinder D, all of these slots being in register, as shown, and the said coin being held within the slot in the said cylinder D by reason of the said slot extending only partly through said cylinder. The hand-wheel *j* is then turned a half-revolution in the reverse direction until its movement is stopped by the engagement of the stops *f* *h* on the toothed disks or segments F G, and this movement of the intermeshed disks or segments has served to bring the cylinder D and the cylindrical coin-shells II I into the relative positions shown in Fig. 3, when the coin E will drop out of the slot *a* in the cylinder D, pass through the central portion of the coin-slot B, and fall into the slot in the coin-shells II I, being held therein by reason of the then lower edge of said coin being in contact with the unslotted portion of the outer shell *m* of the part II. It is now impossible to withdraw said coin, because the solid or unslotted part of the cylinder D effectually closes the passage or coin-slot leading downward from the top slot *u*, and, further, until the coin is received within the slot in the parts II I there can be no operation of the apparatus to which my device is connected, as the mechanism which is to be set in motion is connected to the shaft *s* on the part I, and the shells *m* *n* of the part II move freely within and about the shells *o* *p* of the part I as the hand-wheel *j* is turned back and forth until the coin drops into the described slotted passage in said parts II I. The moment this is done the said parts II I are locked together by the coin, and then as the hand-wheel *j* is again reversed and moved in the first-described direction the parts D and II I are again brought into the relative positions shown in Fig. 2 and the coin drops out through the lower end of the coin-slot B into the receptacle below, and by reason of this interlocking of the parts II and I by the said coin the part I moves, thereby revolving its shaft *s* and actuating, releasing, or otherwise controlling the mechanism connected to said shaft *s*, whatever it may be.

The part A, which I term the "block," need not necessarily be all of one piece, but may be more conveniently formed of two pieces, as the hardened steel top plate M will guard against any tampering with said part A and its contained cylinder D, and there can be no object in withdrawing a coin from the cylinder D when the latter and coin are in the relative positions shown in Fig. 2, as no operation of the device can take place until the coin has been dropped into the posi-

tion shown in Fig. 3, beyond recovery, and the parts H I interlocked, as already described.

It is essential to the proper and consecutive working of my device that the part I of the coin-shells shall always stop at the conclusion of each half-revolution with its described slots in perfect line or register with the coin-slot B in the block A, as otherwise it would be impossible for the next coin from the cylinder D to drop into the said coin-shells, and this result is secured by the described ratchet-wheel J and pawl K, which prevents any backward motion and the teeth of said ratchet-wheel being cut, so that the pawl will hold the said ratchet-wheel and the shaft s, to which it is secured, and the coin-shell I, which is rigid with said shaft, stationary at the precise point named, when the stop on the disk or segment G engages with the stop on the other disk or segment F, and so long as this is accomplished the precise nature of the detent which thus holds the coin-shell I against movement is immaterial; but I have found the described pawl and ratchet to work admirably in practice.

Having thus described my invention, what I claim as new, and desire to secure by Letters Patent, is—

1. In a coin-box for coin-controlled mechanism, the combination with a block having a vertical coin-slot therethrough and cylindrical bores intersecting said coin-slot, and arranged one above the other, of a cylinder in the upper bore having a slot extending partly therethrough and adapted to be brought into register with said coin-slot, and a pair of double concentric coin-shells, nested together within the lower bore and provided with slots extending entirely through all the shells but one, said slots being adapted to be brought into register with each other and with said coin-slot, and the upper cylinder and coin-shells being so connected together that when the former is in position to receive a coin the slotted passage between them is closed, and when said coin has been dropped into the coin-shells, the passage from the top of the block to the slot in said upper cylinder is closed.

2. In a coin-box for coin-controlled mechanism, the combination with a block having a vertical coin-slot therethrough and cylindrical bores intersecting said coin-slot and arranged one above the other, of a cylinder in the upper bore having a slot extending partly

therethrough and adapted to be brought into register with said coin-slot, a pair of double concentric coin-shells nested together within the lower bore and provided with slots extending entirely through the innermost double shell, and through all but one part of the outermost double shell, said slots being adapted to be brought into register with each other and with said coin-slot, means for the simultaneous semirevolution of the said cylinder and the said nested double coin-shells, means for simultaneously stopping this movement at the completion of each semirevolution, and a detent for holding the innermost double shell against movement at all times when its slot is empty.

3. In a coin-box for coin-controlled mechanism, the combination with a block having a vertical coin-slot therethrough and cylindrical bores intersecting said coin-slot, and arranged one above the other, of a cylinder in the upper bore trunnioned or journaled in said block and having a slot extending partly therethrough, and adapted to be brought into register with said coin-slot, a pair of double concentric coin-shells, nested together within the lower bore and provided with slots extending entirely through all the shells but one, said slots being adapted to be brought into register with each other and with said coin-slot, a manipulating-shaft forming the journal of and extending from the outermost double coin-shell through the outer end of said block, a toothed disk or segment on said journal or shaft, another toothed disk or segment on the adjacent projecting trunnion or journal of the described upper cylinder in mesh with the first-named disk or segment, stops on each disk or segment for engagement with each other at each partial revolution of said disks or segments, a shaft forming the journal of and extending from the innermost coin-shell through the inner end of said block, a ratchet-wheel on said shaft, and a pawl for engagement therewith.

In testimony that I claim the foregoing I have hereunto set my hand, at Milwaukee, in the county of Milwaukee and State of Wisconsin, in the presence of two witnesses.
